UNITED STATES PATENT OFFICE.

JOHN V. REAMS, OF MIDLAND, MICHIGAN, ASSIGNOR OF TWO-THIRDS TO
FREDERICK L. BEACHAM AND ROGER W. CLASON, BOTH OF SAME
PLACE.

AUTOMATIC GUARD FOR RAILROADS.

SPECIFICATION forming part of Letters Patent No. 404,435, dated June 4, 1889.

Application filed November 6, 1888. Serial No. 290,115. (No model.)

To all whom it may concern:

Be it known that I, JOHN V. REAMS, a citizen of the United States, residing at Midland, in the county of Midland and State of Michigan, have invented certain new and useful Improvements in Automatic Guards for Railroads; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention has for its object to provide a novel and simplified construction in an automatic cattle or other guard for railroad-crossings; and the nature thereof consists in connecting with the ordinary track-rails auxiliary rails pivoted at their outer ends, the opposite ends thereof provided with forks carrying-links having arms formed thereon, which work in bearings projecting from a shaft having teeth or pickets, said auxiliary rails provided with pins, and springs seated in cups encircling the said pins, as herein-after described and claimed.

In the accompanying drawings, in which corresponding parts are designated by similar letters, Figure 1 is a side view of my invention. Fig. 2 is a top view of the same. Fig. 3 is a sectional view taken on the line $x x$ of Fig. 2, and Figs. 4 and 5 are details thereof.

Referring to the drawings, A represents the ordinary track-rails, and B the road-bed.

Two auxiliary rails C, having channels c , are laid parallel with the rails A, their outer ends being pivoted or hinged in any suitable manner, in order to allow their opposite ends to move to and from the bed of the railroad. Near the inner ends of the auxiliary rails C are secured two forks c' , opposite one another, to which are hinged links D, having arms d formed thereon at right angles, which work in bearings in lugs e projecting from a shaft E. The shaft E is suitably secured in bearings fixed

beneath the rails A, by which means the teeth or pickets secured to the same are thrown below the level of the rails. Cups F are also secured to the rails A, carrying coil-springs f , which bear against the under surface of the auxiliary rails, and are held in position by means of pins f' , secured to the said rails C. A flat spring G is also placed beneath the auxiliary rails, in order to assist in the direct operation of the teeth or pickets. In this construction it will be seen that the links D are connected to the shaft E, opposite one another, by means which will always cause the teeth or pickets to fall away from the train.

It is to be observed that a similar device is used at each side of a crossing.

From the above description it will be seen that as the train approaches the crossing the inner rims of the wheels enter the grooves in the auxiliary rails and press them down, and by means of the links D cause the shaft E to turn or rotate, allowing the train free passage over the teeth or pickets. When, however, the weight of the train is removed, the teeth or pickets will be raised into an upright position by means of the springs f and G.

Having fully described my invention, what I claim, and desire to secure by Letters Patent, is—

In an automatic cattle or other guard for railroads, the combination of the auxiliary rails C, pivoted at one end, forks c' , secured thereto, carrying-links D, provided with arms d , shafts E, secured in bearings and provided with teeth or pickets, lugs e , secured to the said shafts E, for receiving the arms d , and coil-springs f , seated in cups F and held in position by means of pins f' , secured to the auxiliary rails, as and for the purpose described.

In testimony whereof I affix my signature in presence of two witnesses.

JOHN V. REAMS.

Witnesses:

W. M. DAVIDSON,
B. B. BALL.
